Primary Examiner — Jonathan J Han*Assistant Examiner* — Christen Pilar Brown(74) Attorney, Agent, or Firm — Banner & Witcoff, Ltd.(57) CLAIM

The ornamental design for a shoe, as shown and described.

DESCRIPTION

FIG. 1 is a bottom rear perspective view of a shoe showing my new design;

FIG. 2 is an opposite side bottom rear perspective view thereof;

FIG. 3 is a rear view thereof; and,

FIG. 4 is a bottom view thereof.

The broken lines depicting the remainder of the shoe form no part of the claimed design.

1 Claim, 4 Drawing Sheets(56)
